ADVERTISING GLOBE

Jay Stuart Wilkinson, Cincinnati, Ohio, assignor
to The Cincinnati Advertising Products Company, Cincinnati, Ohio, a corporation of Ohio

Application April 5, 1934, Serial No. 719,162

4 Claims. (Cl. 40—132)

This invention relates to an advertising globe of the kind adapted to have illuminating means of the continuous tubular type, commonly known as neon lighting, associated therewith.

5 An object of the invention is to provide means for effectively supporting such lighting means in the globe.

Another object is to provide such supporting means of a resilient nature adapted to preclude 10 shock and jarring and the resultant shattering of the fragile glass tubing utilized in lighting of the character described.

Another object is to provide means of this kind occupying a minimum of space and adapted 15 for simple and efficient manufacture and installation.

These and other objects are attained by the means described herein and illustrated in the accompanying drawing, in which:

20 Fig. 1 is a front elevational view of an advertising globe comprising the means of the present invention and having one of these advertising plates removed therefrom.

Fig. 2 is a cross sectional view taken on the 25 line 2—2 of Fig. 1.

The mounting of neon lighting tubes in positions where considerable vibration, jarring, or shock occurs, has presented a considerable problem in connection with the prevention of injury 30 to and shattering of the tubes due to their heretofore rigid mounting and the resultant transmission of the injurious shocks to the fragile glass. It is obvious that such injury, particularly in locations where there is a frequently recurring cause thereof such as in the lighting 35 globes, commonly utilized on gasoline pumps and adjacent positions, can entail great expense in time, labor and parts as well as in the loss of proper and attractive lighting essential at locations of the kind indicated.

40 The present invention overcomes these difficulties by providing for resilient mounting of neon lighting tubes so that the danger of shattering of the neon lighting tubes by vibration, jar or shock is eliminated.

45 With reference to the drawing, the type of globe commonly utilized for locations of the kind indicated comprises a base 5 and a metal rim 6 associated therewith and adapted to support glass advertising plates 7 in substantially parallel spaced relationship. The lighting tubes may be of the continuous kind formed to extend 50 in two sections 8 and 9, one each, around the interior of the globe adjacent the peripheries 55 of the plates 7. This tubing may extend trans-

versely across the globe as at 10 and may have its ends terminating in an adjacent position as at 11, from which ends suitable wire 12 projects downwardly into a transformer 13 commonly required in connection with lighting of the kind 60 in question. Said transformer may be conveniently positioned adjacent the base 5.

For resiliently positioning the continuous glass tubes, there are provided, according to the present invention, a number of arcuate resilient 65 support strips 14 disposed at intervals around the interior face of the rim 6. The central section of each strip 14 is suitably secured, such as by spot welding, to the central section of the rim 6 as at 15. The end portions 16 and 17 70 of each support strip, extend clear of the rim and a pair of opposed hook-like members 18 and 19 are formed, one at each end 16 and 17.

Adjacent the hook-like members described, the support strip may be provided with small aper- 75 tures 20.

The sections 8 and 9 of the light tubing are adapted to be disposed against the outer faces of the hook-like members 18 and 19 on the respective sides of the globe. Small wires 21 may 80 be passed around the tubing and through the apertures 20 and thereafter twisted together for attaching the tubing to the support strips 14. It is obvious that other suitable means for associating said strips and tubing may be employed. The positioning of the hook-like members 85 18 and 19 behind or inwardly of the tubing sections 18 and 19, precludes the formation of shadows on the advertising plates.

It has been stated above that the outer portions of the support strips 14 extend clear of the rim 6 and of all other contact which might result in the direct transmission of vibration and shock to the glass tubes, such jarring being caused, for example, by passage of heavy vehicles, the operation of the gasoline pump with which the globe might be associated, or other similar causes. It is apparent, however, that although the glass tube is thus suspended, as it were, its positioning is yet secure and very effective for 90 the achieving of peripheral lighting effects on the globe.

Possible modifications present themselves on consideration of the means herein described but these are believed to be comprised within the 105 spirit and scope of the present invention.

What is claimed is:

1. An advertising globe comprising a metal rim, a pair of spaced oppositely-disposed advertising plates supported thereby, illuminating 110

means of the continuous tubular type enclosed within said rim and plates and disposed adjacent the peripheries of the plates for illuminating the adjacent parts thereof, a plurality of 5 spaced resilient support strips extending transversely of the inner face of said rim and adapted to resiliently hold said tubular illuminating means in position, said strips having their central portions secured to the rim and their end 10 portions in spaced unattached relationship therewith, and means at the ends of the strips for engaging said illuminating means.

2. An advertising globe comprising a metal rim, a pair of spaced oppositely-disposed advertising plates supported thereby, illuminating means of the continuous tubular type enclosed within said rim and plates and disposed adjacent the peripheries of the plates for illuminating the adjacent parts thereof, a plurality of 15 spaced resilient support strips extending transversely of the inner face of said rim and adapted to resiliently hold said tubular illuminating means in position, said strips having their central portions secured to the rim and their end 20 portions in spaced unattached relationship therewith, hook-like members formed at the ends of said strips and adapted to be positioned be- 25

hind or inwardly of said illuminating means to preclude shadow formation on said plates, and means for engaging the illuminating means and attaching the latter to the hook-like members.

3. As a new article of manufacture, a support for resiliently positioning "neon" tubes and the like interiorly of rim-type advertising globes, said support consisting of an arcuate resilient strip adapted to have its central portion secured to the rim of the globe with the end portions thereof extending clear of the rim, said end portions being formed to provide hook-like members adapted to be positioned behind or inwardly of the "neon" tubes to preclude shadow formation on the advertising plates, said tubes being suitably secured as by wiring, to said hook members.

4. The combination, with an illuminable globe, of a rim, illuminating means of the continuous tubular type, a resilient support strip attached to the rim and having a portion thereof extending in spaced unattached relationship with the rim, and means associated with said unattached portion for engaging and resiliently positioning said illuminating means.
